Specification for Design.

Patented Mar. 28, 1911.

Application filed January 11, 1911. Serial No. 602,113. Term of patent 14 years.

To all whom it may concern:

Be it known that I, WILLIAM N. GOLDHAMER, a citizen of the United States, residing at the city of St. Louis, State of Missouri, have invented a new, original, and ornamental Design for a Door-Frame and Doors for Stove-Ovens, Warming-Compartments, and the Like, of which the following is a specification, reference being had to the accompanying drawings, forming a part hereof, in which—

Figure 1 is a front elevational view of a

door-frame and doors for stove-ovens, warming-compartments, and the like, embodying my new design; and Fig. 2 is an end view of the same.

I claim—

The ornamental design for a door-frame and doors for stove-ovens, warming-compartments, or like articles, as shown.

WILLIAM N. GOLDHAMER.
